(57) **CLAIM**

The ornamental design for a ski tip connector, as shown and described in the Figures.

DESCRIPTION

FIG. 1 is a perspective view of a ski tip connector for connecting the tips of two snow skis together;

FIG. 2 is a front elevational view thereof, the rear elevational view being a mirror image thereof;

FIG. 3 is a left side elevational view thereof, the right side elevational view being a mirror image thereof;

FIG. 4 is a top plan view thereof; and,

FIG. 5 is a bottom plan view thereof.
